DESIGN FOR A RING OR SIMILAR ARTICLE

Jean Schlumberger, New York, N. Y.

Application September 26, 1941, Serial No. 103,515

Term of patent 3½ years

To all whom it may concern:

Be it known that I, Jean Schlumberger, a citizen of France and a resident of the United States of America, residing in the city of New York, county of New York, and State of New York, have invented a new, original, and ornamental Design for a Ring or Similar Article, of which the following is a specification, reference being had to the accompanying drawing, forming part hereof, wherein:

Figure 1 is an edge elevational view of a ring showing my new design with the movable circular elements in a flat position.

Figure 2 is a top plan view thereof.

Figure 3 is an edge elevational view of the ring shown in Figure 1 with the movable circular elements in a raised position, and

Figure 4 is a top plan view of the ring as shown in Figure 3.

I claim:

The ornamental design for a ring or similar article, substantially as shown and described.

JEAN SCHLUMBERGER.
